UNITED STATES PATENT OFFICE.

FRANK S. INGOLDSBY, OF ST. LOUIS, MISSOURI, ASSIGNOR TO THE
INGOLDSBY AUTOMATIC CAR COMPANY, OF ST. LOUIS, MISSOURI,
A CORPORATION OF WEST VIRGINIA.

DUMP-CAR.

No. 799,651.

Specification of Letters Patent.

Patented Sept. 19, 1905.

Application filed January 30, 1905. Serial No. 243,191.

To all whom it may concern:

Be it known that I, FRANK S. INGOLDSBY, a citizen of the United States, residing at St. Louis, in the State of Missouri, have invented 5
a certain new and useful Improvement in Dump-Cars, of which the following is a full, clear, and exact description, reference being had to the accompanying drawings.

The object of this invention is to provide a 10 simple and efficient mechanism for receiving the impact of dropping doors of dump-cars and hold the same at various inclinations, as desired.

The invention is particularly applicable to 15 dump-cars of what are known as the "Ingoldsby" type, these cars having a central longitudinal beam and doors hinged at the opposite edges thereof and arranged to swing downward.

20 The invention is an improvement on the structure shown in my prior application, Serial No. 238,300, filed December 27, 1904, and relates particularly to a gravity-lock for holding the bumpers in various positions.

25 In the drawings, Figure 1 is a cross-section through a car of the Ingoldsby type having my bumping mechanism. Fig. 2 is an enlarged view of the portion of the mechanism concerned with the lock, being taken from the 30 same position as Fig. 1. Fig. 3 is a side elevation of such lock, being a section along the line 3 3 of Fig. 1. Fig. 4 is a cross-section on the line 4 4 of Fig. 3.

The car has a longitudinal beam A, to the 35 lower opposite edges of which are hinged the dumping-doors B. These doors are adapted to have their outer edges abut the sides C of the car. The doors may be held in closed position by hooks D, pivoted to the sides of the 40 car and engaging the projecting ends of floor-beams E, secured to the under side of the doors.

Secured to the under side of the central beam A is a vertical metal sheet F. This sheet 45 is shown as held in place by bolts f and an angle-flange f', secured to the plate. This plate carries the bumpers G, which receive the impact of the doors, each door having on its under side a stiff leaf-spring H to cushion the 50 blow and each bumper having an enlarged head g to receive the spring.

The shanks of the bumpers are flat bars engaging the surface of the sheet F and retained

against the sheet by guiding-stirrups f² and f³, riveted to the sheet. A strengthening-angle f⁴ may be applied to the lower end of the sheet. The shanks of the bumpers are in the shape of an arc about the pivot of the corresponding door, so that they may be shoved through their stirrups to cause the bumpers 60 to project varying amounts and still always be in line with the springs H on the doors.

To hold the bumpers in the desired position, I provide a gravity-lock J, which is a bar pivoted on a bolt L, secured to an angle-plate f⁵, 65 carried by the plate F, in the opposite side from the stirrups, the same rivets f⁶ holding the plate f⁵ and the stirrup f³. The bar J is adapted to enter any of a series of notches g' on the under edge of the bumper, being held 70 in this position by the greater weight of the other end thereof, which is elongated or otherwise counterweighted for the purpose. If found desirable, the long arm may carry an additional counterweight slipped over it and 75 secured to it either rigidly or adjustably. This bar J holds the bumpers G very firmly in position. At the same time it is easy to release the bumpers, even when the doors are resting on them, should any clogging of the material 80 at the door-hinges require this. To accomplish this, it is only necessary for the attendant to strike a blow upon the under side of the bar J, knocking it up into the position shown in dotted lines in Fig. 3. The attendant may perform this operation with perfect safety while standing under the car beneath the central beam, which protects him. Another advantage of this lock is that it is 85 permanently attached to the car and is not 90 liable to become out of order.

It will be noticed that the spring H is formed peculiarly, its outer portion descending abruptly from the door and the inner portion inclining gradually and by a longer 95 reach to the door. The bend of the spring is great enough so that the direction of the incline therefrom toward the pivot of the door is upward of the plane passing from the bend through the pivot. The reason for this peculiar shape is the following: When the quadrant is run out to stop the door at one of its intermediate positions, the quadrant becomes, in effect, a beam fixed at one end, and any pressure vertically downward on the end 100 of the bumper causes a severe tensile strain 105

along its upper edge at the stirrups. The spring, however, engages the lower edge of the bumper-head and below that point continues to recede from the door, so that it makes, in effect, an inclined shoulder resisting any downward movement of the bumper. The downwardly-vertical strain being thus neutralized, the quadrant is left in pure compression, as it should be.

10 I claim—

1. In a dump-car, the combination of a dumping-door, a bumper therefor, and a gravity-lock for the bumper.

2. In a dump-car, the combination of a dumping-door, an adjustably-positioned bumper, a support for the bumper, a gravity-lock for the bumper carried by said support.

3. In a dump-car, the combination of a dumping-door, a bumper therefor, said bumper having a plurality of notches, and a locking-bar adapted to enter any of said notches.

4. In a dump-car, the combination of a dumping-door, a bumper having a plurality of recesses in its shank, a support for the bumper, and a pivoted locking-bar adapted to enter any of said recesses.

5. In a dump-car, the combination of a dumping-door, a bumper having an arcual shank with notches on one edge, a guiding-support for said bumper, and a pivoted bar adapted to enter one or another of said notches.

6. In a dump-car, in combination, a dumping-door, a bumper, a support for the bumper slidably carrying it, a pivoted locking-bar carried by said support, said bar being adapted to enter a notch in the bumper to hold it in place.

7. In a dump-car, the combination of a dumping-door, a depending sheet, a bumper having an arcual shank lying alongside of said sheet, a guiding-stirrup secured to said sheet and embracing said shank, and a gravity-lock pivotally carried by said sheet and adapted to engage said shank.

45 8. In a dump-car, the combination of a dumping-door, a depending sheet, a bumper having a shank lying alongside of said sheet, a guiding-stirrup secured to said sheet and em-

bracing said shank, and a gravity-lock adapted to engage said shank, said lock being pivoted to an angle-plate secured to the sheet on the opposite side thereof from the stirrup.

9. In a dump-car, the combination of a dumping-door, a bumper having an arcual shank, a support for the bumper having a stirrup extending across the shank of the bumper, said bumper having a series of notches in its edge, an angle-plate carried by said support, a bar pivoted to said plate and adapted to enter one of said notches, said bar having its other end heavier to provide a gravity-lock.

10. In a dump-car, the combination with the stationary part of the car, of a dumping-door pivotally carried thereby, a depending vertical plate carried by said stationary part, a bumper having a shank lying alongside of said plate, said shank being arcual about the pivot of the door, a stirrup carried by said plate and embracing and guiding said shank, said shank having notches on its under edge, and a bar supported by said sheet on a pivot which is on the opposite side of the sheet from said stirrup, said bar having the upper edge of an end adapted to enter any of said notches, and having its other end acting as a counter-weight to hold the bar in position by gravity.

11. In a dump-car, in combination, a dumping-door, a bumper therefor and a spring carried by the door for impingement against the bumper, the parts being shaped to counteract the strain upon the bumper which tends to bend it.

12. In a dump-car, in combination, a pivoted dumping-door, a spring carried on the under side thereof, a bumper beneath the door adapted to be engaged by said spring, said spring being formed to counteract the vertically-downward strain in the bumper which the impinging door would otherwise cause.

In testimony whereof I hereunto affix my signature in the presence of two witnesses.

FRANK S. INGOLDSBY.
